UNITED STATES PATENT OFFICE.

FRANK H. ELLIS, OF CHICAGO, ILLINOIS.

SAFETY HORSE-DETACHER.

SPECIFICATION forming part of Letters Patent No. 740,111, dated September 29, 1903.

Application filed May 10, 1902. Serial No. 106,685. (No model.)

To all whom it may concern:

Be it known that I, FRANK H. ELLIS, of Chicago, in the county of Cook and State of Illinois, have invented certain new and useful 5 Improvements in Safety Horse-Detachers; and I do hereby declare that the following is a full, clear, and exact description thereof, reference being had to the accompanying drawings, and to the letters of reference marked 10 thereon, which form a part of this specification.

This invention relates to improvements in safety horse-detachers designed to afford means for readily releasing a horse from a 15 vehicle in case of an accident, such as where a horse falls down while attached to the vehicle or in case of a runaway.

The invention consists in the matters hereinafter set forth, and more particularly pointing 20 ed out in the appended claims.

In the drawings, Figure 1 is a plan view of a pair of buggy-shafts and whiffletree, showing my invention applied thereto. Fig. 2 is a rear view of the device. Fig. 3 is a plan view 25 of the parts shown in Fig. 2. Fig. 4 is a section on line 4-4 of Fig. 3. Fig. 5 is a view similar to Fig. 4 with the parts in changed position. Fig. 6 is a view showing my invention as forming a part of the connections between an evener and the whiffletree.

As shown in said drawings, A A designate 30 a pair of thills connected by the usual cross-bar A', and B designates a whiffletree of ordinary form pivoted to the cross-bar by a whiffletree-bolt b.

C C designate my improved safety-detachers connected one with each end of the whiffletree.

The devices at both ends of the whiffletree 40 are alike in their construction, and in the following description thereof but one will be referred to. Said device consists, essentially, of a head C', which is provided on its outer side with separated arms C² C², arranged vertically one over the other, a block C³, which is inserted between said arms provided at its opposite ends with pivot-studs c, which engage pivot-apertures in the outer ends of the arms, a spring-pressed plunger D, which

50 passes centrally through said head, and an attaching-arm C⁴, attached to or formed upon the inner side of the block C³ and adapted

to have interfitting connection with said plunger D. As herein shown, the head is attached to the whiffletree by means of a shank E, 55 which is made integral therewith. Said shank is provided at its end remote from the head with an axial socket e, within which the end of the whiffletree fits. The end of said whiffletree is desirably reduced, as shown, to 60 an extent equal to the thickness of the walls of the shank, so as to form a flush joint between said shank and whiffletree. Said shank E is provided adjacent to the head with an axial recess E', within which is located the 65 plunger D. E² designates a spiral spring which is located within an enlarged part of said recess and surrounds said plunger and bears at one end against an interior shoulder e' in said recess and at its other end against 70 a shoulder d on said plunger. As herein shown, the plunger is provided at its extreme outer end with a socket e², which is made of such size as to receive the reduced end of the arm C⁴ of the pivot-block C³. Said plunger 75 fits closely in the bearing-apertures in the head and shank through which it passes, thereby preventing lateral movement thereof. It is obvious that a reversal of such interfitting connections will produce the same 80 results—that is to say, the arm may have a recess in the end thereof to receive the plunger D.

F designates a pin which passes through a slot e⁴ in the rear wall of the shank which intersects the recess E' and which pin is connected at its other end with the plunger D and is provided at its outer end with a loop or eye e⁴. G G designate cords or straps each of which are attached at one end thereof to 90 the eye of one of said pins F and which cords engage between their ends rings g or other suitable guiding means located near the center of the whiffletree. In rear of said whiffletree said cords G are joined to a single cord 95 G', the other end of which is contained within the vehicle-body and within reach of the person seated in the vehicle.

H H designate the harness-traces which are adapted to fit at their rear ends over the 100 attaching-arms C⁴ of the pivot-block and by means of which they are secured to said detachers.

The operation of the device is as follows:

The traces when the horse is hitched to the vehicle are engaged with the attaching-arms C⁴ of the pivot-block, and by reason of the interfitting connections between said arms and 5 the plungers D and the fact that said plungers are held from lateral movement in their bearings in the head said arms are held rigidly in the positions shown in Figs. 2 and 4, and while in such positions the traces can- 10 not be detached from the whiffletree. In case of an accident—as, for instance, if the horse should accidentally fall or if it be desired for any other reason to detach the horse from the vehicle—the driver will grasp the 15 cord G' and pull it rearwardly, which will act to simultaneously retract both plungers D and move the same out of engagement with the attaching-arms C⁴. At this time said blocks C³ will be free to turn or rotate on 20 their pivots, and a forward pull on the traces will cause said blocks to rotate in a forward direction, so that the traces will slip off the arms and be entirely disengaged therefrom.

My improved detacher may be used as a 25 part of the connections between an evener and a whiffletree, as well as in the location shown in the figures just described, and I have shown in Fig. 6 the said detacher so applied to an evener and whiffletree. The de- 30 vice is made the same as shown in the previous figures and may be attached to the evener in the same manner, and the parts are therefore designated by like reference-letters. In this case the whiffletree I is pro- 35 vided with the usual trace hooks or lugs and is provided centrally thereof with a clip I', to which is connected by a swivel-joint a ring or loop I², which is adapted to pass be- 40 tween the arms C² of the head and engage the attaching-arm C⁴. A cord G is attached to the pin F and will pass through a guide pulley or loop near the center of the evener in a manner similar to the arrangement shown in Fig. 1 and be continued to the vehicle- 45 body within easy access of the person seated therein. The operation of this device will of course be in all essential respects like that before described, it being understood that the whiffletree will be released instead of the 50 traces.

Instead of the shank E being used as the means for attaching the device to the whiffletree or evener, as the case may be, other means may be employed by which the same 55 may be rigidly attached to said evener or whiffletree, and I do not wish to be restricted to the construction herein shown. Said shank, however, is a convenient means of fixing the device to the swingletree or evener, for the 60 reason that it affords a socket contained within the same for the plunger D and without the

necessity of greatly increasing the length thereof. Obviously the same results would be produced if the head were made integral with the whiffletree or evener with which it 65 is used.

I claim as my invention—

1. A safety horse-detacher comprising a head, vertically-separated arms thereon, forming between the same a recess which is open 70 at both its front and rear, a rotative block in said recess journaled in said arms, an attaching-arm projecting inwardly from the block, and a spring-pressed plunger in alinement with said attaching-arm which has interfitting 75 engagement at its two ends with the arms.

2. A safety horse-detacher comprising a head, separated arms thereon, a rotative block between said arms and journaled therein, an attaching-arm projecting inwardly 80 from said block, a shank connected with said head and provided with an axial recess in alinement with said attaching-arm, a spring-pressed plunger in said recess, which has interfitting engagement end to end with said 85 attaching-arm, the inner end of said recess being reduced to provide a guide-bearing for the plunger, and the inner end of the shank being provided with an axial socket adapted to receive the part to which the detacher is 90 attached.

3. The combination with an evener and a whiffletree, of means for detachably connecting the same comprising a head connected with the evener, vertically-separated arms 95 thereon, a rotative block between said arms, an attaching-arm projecting inwardly from said block, a spring-pressed plunger engaging said attaching-arm end to end and having interfitting connections therewith, a clip on the 100 whiffletree and a loop which is connected with the whiffletree and fits over said attaching-arm.

4. A safety-detacher comprising a head, vertically-separated arms thereon forming between the same a recess which is open both at its front and rear, a rotative block in said recess journaled in said arm, an attaching-arm projecting inwardly from the block, and a spring-pressed plunger in alinement with said 105 attaching-arm which has interfitting engagement end to end with said arm, and a laterally-directed pin on the plunger adapted for attachment thereto of a cord or cable.

In testimony that I claim the foregoing as 115 my invention I affix my signature, in presence of two witnesses, this 8th day of May, A. D. 1902.

FRANK H. ELLIS.
